(57) **CLAIM**

I claim the ornamental design for the surgical tool, as shown and described.

DESCRIPTION

FIG. 1 is a top plan view of the surgical tool;

FIG. 2 is a bottom plan view of the surgical tool;

FIG. 3 is a top perspective view of the surgical tool;

FIG. 4 is a bottom perspective view of the surgical tool;

FIG. 5 is another bottom perspective view of the surgical tool;

FIG. 6 is a front and rear end perspective view of the surgical tool; and,

FIG. 7 is a left and right side perspective view of the surgical tool.
